VERTICAL SELF-PRIMING PUMP

Harry E. La Bour, Elkhart, Ind.

Application March 8, 1944, Serial No. 525,529

25 Claims. (Cl. 103—113)

The present invention relates to self-priming centrifugal pumps.

The broad concept of the present invention is to improve the construction and operation of self-priming centrifugal pumps of the class described in my prior patent, No. 1,578,236, and to embody therein a kinetic liquid seal for the impeller shaft.

A specific object is to provide a pump employing a kinetic liquid seal in which the liquid containing walls of the pump body may be constructed interchangeably of metal or of porcelain or the like.

The preferred form of pump herein illustrated is a vertical pump suitable for acid service, but the improvements herein disclosed are intended to be employed in other types of self-priming pumps and other fields of use where applicable.

Centrifugal pumps of the self-priming type have certain inherent problems, the chief one of which is the sealing of the shaft. A self-priming pump imposes its suction upon the shaft seal and any leakage at that point reduces the efficiency and the effective lift of the pump. In the pump of the present invention a novel form of liquid seal and impeller embodying the principle of my copending application, Ser. No. 439,308, filed April 17, 1942, is utilized. Previous embodiments of that principle have involved certain complexities and difficulties of construction and servicing which it is one of the objects of the present invention to simplify and obviate. One specific difficulty is to establish an air tight seal of certain jointed parts subject on one side to suction, but required to be separable for servicing and renewal of parts. The present seal, shaft, and impeller construction is designed to be suitable for embodiment in pumps of various material, such as of cast metal or of porcelain, or of other suitable materials. In the various embodiments herein disclosed, the structure has been organized to simplify the problem of construction, and more importantly, the problem of servicing, and renewal of the impeller, without danger of introducing leaks which would seriously impair the efficiency of the pump. The preferred organization of the impeller and seal housing is such as to permit of ready removal of the shaft, the impeller, and the seal as a unit. Replacement may then be made in the field by unskilled attendants. This is of practical importance. The seal herein disclosed is capable of operating without losing its liquid, and without discharging liquid during any phase of operation. The seal may be constructed in various diameters, each to be operative to maximum suction over a fairly wide range

of speeds. For example, a disk of about 4 1/4" while designed for 3450 R. P. M. is operative with water and under high vacuum down to 2900 R. P. M., and at lowered vacuums at speeds as low as 1750 R. P. M. The effectiveness of the seal increases directly as the specific gravity. Reference herein to the conditions under which the seal operates is to be understood to relate to the employment of water as the sealing liquid. Obviously, the specific gravity of the liquid must be taken into account in determining the speeds and dimensions required to withstand a given pressure difference.

The seal using a 7" disk may be used to hold maximum suction at 1750 R. P. M. While the impeller diameter and the seal channel diameter are illustrated as being the same, the impeller diameter may be greater than the seal channel diameter if so desired.

15 A second major problem of pumps of this class has to do with priming. Pumps of this class are usually subjected to tests to determine at some predetermined speed or range of speeds for which the pump is designed, the characteristics of rate 20 of priming, that is, the rate of air removal, the maximum dry suction attainable, and the efficiency of pumping liquid for which the pump is designed. The requirements for rapid priming, the requirements for maximum dry suction and 25 the requirements for high pumping efficiency are divergent. Features favorable to high pumping efficiency are generally unfavorable, or even contradictory, to good air handling ability, and/or high, dry suction.

30 35 From numerous tests of the air handling ability of self-priming pumps operating under the hydraulic balance principle of my aforesaid patent, I have observed that when the test extends to maximum dry suction the priming operation 40 tends to proceed through three successive stages. The first stage, assuming the pump starts with atmospheric pressure on both its suction side and on its discharge side, involves the initial withdrawal of air. As soon as the impeller starts to 45 rotate, it throws substantially all of the priming liquid which is trapped in the suction connection and the impeller casing out into the discharge chamber or separator. Thereupon liquid tends to flow back through the main and priming throats 50 into contact with the impeller. However, the tendency of the impeller to block reentry, both by the blocking effect of the blades and by the impact effect of driving liquid back through the aforesaid port slows down the reentry of priming 55 liquid. The force tending to feed liquid from

the separator back through the priming throats is only the small static head of liquid in the separator. The lack of ability of the liquid to return in sufficient amount to make up an adequate amount of air carrying mixture to fill the discharge throat results in a phase of operation known as a "priming stall." The air removal during this stage is slow. However, as soon as enough air has been removed to produce a substantial pressure difference, that pressure difference, added to the static head, begins to return enough liquid to produce a flow of mixture which fills the discharge throat, that is, the main throat. That produces the second stage of priming. During this stage, air removal is rapid.

The third stage begins when the pressure difference is so great as to produce an undesirably large flow of liquid. The ratio of liquid to air begins to cut down the rate of air removal. This reduction in rate of air removal is due to both the expanded state of the air and the excessive return flow of liquid. As the vacuum increases, the amount of air which is discharged with the liquid vehicle decreases, so that at maximum vacuum there is no air removed. The pump is not able to retain a mixture of air and liquid up to the point of discharge and to discharge the mixture out of the impeller.

During the aforesaid "priming stall" it appears from my investigation of the difficulty that so small an amount of liquid reenters that the density of the medium, i. e., mixture of air and water is so low that no effective discharge pressure is developed in the main throat. In the case of a horizontal shaft pump the air in the impeller casing tends to gravitate up through the main throat and through the liquid in the separator and gradually an orderly circulation is established. In the present form of vertical shaft pump the establishment of an orderly circulation, i. e., reentry of liquid at the priming throat, formation of a mixture and discharge at the main throat is much more difficult. It appears that upon initial emptying of the impeller chamber and filling of the same with air, and mixing of the air with a small amount of remaining and reentering liquid creates a slight internal pressure. This internal pressure may not be great enough to overcome even the small head of liquid in the separator. Air appears to be driven into the throats, but with insufficient force to establish a substantial discharge. This air pressure appears at times to establish an air lock in the priming throat which discharges downwardly, and this air lock prevents inflow of liquid. At the main throat the pressure is so low as to fail to establish an effective discharge, and the impeller tends to drive back liquid that might enter at this point. The result is that the initial pickup of suction is very slow as compared to the rapid air evacuation that occurs as soon as an orderly circulation is established.

I have discovered that it is possible to break the "priming stall," i. e., greatly shorten the time required to establish an orderly priming flow by either one of two methods. One method involves introducing liquid through an auxiliary opening which may be at any suitable place which will let liquid from the separator flow into the impeller at a point not subject to air lock, as, for example, through the clearance around the sealing box or channel member. The other method involves the provision of an opening which allows air to gravitate out of the throat

of one of the discharge passageways. This, for example, may be a hole or slot in the upper wall of the main passageway at a point near its junction with the impeller chamber. The first

5 method of overcoming the priming stall involves introducing liquid into the impeller through an auxiliary port preferably by way of the clearance of a rotating part with a stationary part of the casing. This opening may serve as a continuously 10 open port with the pressure continuously in one direction, though preferably the pressure is reduced as the pump is primed. Preferably the auxiliary opening comprises an open port in which the pressure reverses upon the pump filling 15 its suction with liquid and attaining its discharge pressure. Thus, by utilizing the hydraulic balance principle upon the aforesaid auxiliary port the inefficiency which would result from a constantly open bypass between discharge and suction 20 is reduced or avoided. At the same time, the "priming stall" is substantially eliminated. This is a feature of practical importance.

The second method above mentioned is perhaps the simplest and it may be used separately 25 or in conjunction with the first. Each method alone cuts to about half the time previously required for overcoming the "priming stall."

A further problem of pumps of this type has to do with what happens when the pump impeller slows down to a stop, and the discharge and suction columns drop back due to gravity. One difficulty with self-priming pumps in general is the tendency for the liquid to drop back so rapidly as to pull the priming charge of liquid 30 out of the pump, particularly by the rush of air that follows the retreating column of liquid down the suction pipe. Heretofore, solution has been attempted by increasing the size of the intake trap, so that the air following the column down 35 should bubble up through the liquid in the intake trap, and leave sufficient liquid for the succeeding priming operation. While that was possible with a single pair of throats, and in pumps of relatively small capacity, it is found that in 40 the present design of pump wherein multiple pairs of throats are employed, and particularly where the pump is of the vertical type, the liquid tends to go out of the separator, the pump and the intake trap so rapidly, and with such a rush 45 of air as to require too large an intake trap to be practical. I am aware that it has been proposed to employ a valve in the suction pipe, or suction connection of the pump, which will 50 check the return flow, or, as disclosed in my co-pending application, Serial No. 439,308, filed April 17, 1942, to insert a flow retarder in the 55 suction connection. But I have discovered that in a pump of the type employing a liquid seal of the character herein employed, any checking 60 of the outward flow on the intake side is likely to produce a flooding of the seal, which is undesirable. In fact the dropping of the discharge column may produce a slug or hammer effect which 65 squirts liquid out of the gap between the shaft and the sleeve in an undesirable manner. This is particularly objectionable in the event that the liquid being handled is of a corrosive or inflammable character. I have discovered that a retardation of the flow of liquid back into the 70 pump from the discharge pipe produces the desirable effect of gradually feeding liquid back into the separator, while allowing the column in the suction pipe to drop as rapidly as it will, the vacuum in the intake being broken by air 75 drawn down through the liquid seal. While this

would appear to empty the seal of liquid, nevertheless the organization of the pump is such that liquid flowing into the impeller chamber from the separator fills the seal even though the intake trap should be completely emptied of liquid by the outrush of air entering through the sleeve and the sealing gap.

With this arrangement it is possible to reduce the intake trap to a relatively small chamber of only sufficient size to give good distribution around the impeller. The pump is thereby rendered more compact, or for a given volume, greater space is permitted in the separator where the necessary work of air elimination from the priming liquid is carried on.

So far as I am aware no one has seen how to build a self-priming porcelain pump, much less how to make the parts which must necessarily be made of metal adaptable to interchangeable use for a porcelain pump as well as a metal pump. The pump of the present invention accomplishes this. A difficulty with porcelain is the inability to endure a concentrated stress particularly in tension. I conceived the possibility of employing porcelain in such a manner as to avoid concentrated stresses and to make the pump producible in porcelain. The pump is divided into parts which are producible in porcelain and the parts are shaped to withstand the fluid pressures and the mechanical stresses to which the parts are subjected. The parts which must be made of metal involve a minimum in contact with the liquid to be pumped. This results in a great saving in critical materials, at present a very desirable object.

Another difficulty which I have encountered in pumps of this character, particularly vertical self-priming pumps, is the problem of preserving the bearings against contact with the liquid being pumped. The preferred embodiment of the pump herein illustrated is designed for handling corrosive liquids, and it is highly important to keep the liquid and vapor therefrom out of the bearing space, otherwise corrosion of the bearings, particularly of the anti-friction type, results in rapid wear and destruction of the same.

I have provided a simplified and novel form of shaft bearing seal against the entry of liquid which might creep or be projected up along the shaft. This comprises a circular channel sealed with lubricating oil, preferably that which has passed through the bearings and washed them out, and a stationary ring which contacts with the oil in the channel to maintain a seal.

Certain mysterious failure of the bearings originally encountered, was finally diagnosed as due to breathing induced by changes in temperature in the parts defining the hollow space between the shaft and the bearing barrel causing corrosive vapors given off by the liquid pumped to be drawn into the said space and condensed in contact with the anti-friction bearings with consequent corrosion of the same. Numerous expedients were tried to overcome this, but the final solution herein embodied is a removable filler block, which while permitting the withdrawal of the bearings, serves the purpose of reducing the space to so minor a clearance that the breathing effect is substantially eliminated, and no vapors are drawn into the bearings.

The present pump is organized to permit the employment of porcelain for the parts which constitute the structural walls of the chambers. Those parts which require high strength and resistance to shock must necessarily be made of

metal. Such parts are the impeller and its shaft and driving parts, the sealing sleeve and disk and channel member.

Other and concomitant improvements will be apparent from the following detailed description and the claims.

Now in order to acquaint those skilled in the art with the manner of constructing and operating the device embodying my invention, I shall describe, in connection with the accompanying drawings, a specific embodiment of the same.

Figure 1 is a vertical, longitudinal section through the preferred embodiment of the present invention;

15 Figure 2 is a plan view of a detail, namely, a locking washer;

Figure 3 is a fragmentary, sectional view, showing a modified form of auxiliary priming port;

20 Figure 4 is a top plan view of the impeller and sealing box housing, with unitary ducts and associated flanges;

Figure 5 is an elevation of the same on the line 5—5 of Figure 4;

25 Figure 6 is a vertical, longitudinal section of the impeller and sealing box housing, taken on the line 6—6 of Figure 4;

Figure 7 is a diagrammatic developed section through the center line of main throat and duct taken on the line 7—7 of Figure 4;

30 Figure 8 is a similar diagrammatic developed section through the center line of the priming throat and duct, taken on the line 8—8 of Figure 4;

Figure 8A is a fragmentary section on the line 35 8A—8A of Figure 4; and

Figure 9 is a vertical longitudinal section similar to Figure 1 through a porcelain pump embodying the present invention.

The pump shown in Figure 1 comprises a generally cylindrical body 1 having cylindrical side walls 2 joined to a bottom wall 3, and an upper closure wall 4, the upper and lower walls 3—4 being generally transverse to cylindrical walls 2. The cylindrical walls 2 have an extension 5 above the upper transverse wall 4, which extension wall 5 is provided with an annular flange 6 upon which rests a supporting ring 7 for mounting the bearing barrel 8, and the motor support 9. The motor support is adapted to receive a vertical electric motor, not shown, direct coupled to the driving shaft 60.

The body of the pump is divided into an upper section 10, and a lower section 12, joined together in the particular embodiment shown in Figure 1 by the clamping flanges 13 and 14, which are piloted together for ready assembly as indicated at 15. A thin gasket between flanges 13, 14 may be provided.

A centrally disposed and concentric annular wall 16 integral with the upper closure wall 4, or the adjacent side walls 2 if preferred, defines an intake trap or intake chamber 17 which communicates through an opening in the said upper wall 4 with an intake or suction connection 18 which is shown in dotted lines in Figure 1 for the sake of clarity of illustration. In the actual pump the neck or suction connection 18 is disposed generally diametrically opposite the discharge neck or connection 19, but obviously the 70 angular position of the two necks with respect to each other is optional.

The space inside the hollow body and outside of the intake chamber 17 forms a separator chamber 20. This separator chamber 20 functions when the pump is not in operation to trap

liquid, and in the operation of priming to disentrain gas from liquid as is well understood by those skilled in the art.

The intake chamber wall 16 has an inwardly extending flange 22, the lowermost surface of which, indicated at 23, is finished off to form the top side plate of the impeller chamber. The impeller chamber is defined by a cup-shaped member 24, which has cylindrical walls, the upper margins of which embrace the depending, cylindrical surface 26 of the wall 16, and substantially abut the annular radial shoulder 26, also formed on said wall 16. The cup-shaped member 24 has certain openings and ducts for cooperation with the impeller blades 27. Suffice it to say at this point that the openings 28 are ports for the main discharge ducts 28a, 28a, and the openings or ports 29 constitute the priming ports which open into the priming ducts 29a, 29a. The ducts 28a extend outwardly substantially in the plane of the openings 28, and discharge their contents above the flange segments 30, 30, whereas, the priming ducts 29a, 29a are led downwardly, and open out below the flange segment 30, as will be apparent from Figures 4 and 8. The throats 28 and 29 are narrow slot-like throats embodying the invention of my prior Patent No. 2,291,478, and of my copending application, Serial No. 439,308, filed April 17, 1942, these openings 28 and 29 being of less width than the width of the blades 27. The oblong outline 28b in Figure 7 is a development of the actual throat opening 28. Likewise in Figure 8 the oblong outline 28b is a development of the actual throat opening 29. It is to be observed that the throat openings 28 and 29 are of approximately the same width. They are located in the part of the impeller chamber 24 which has only a running clearance with the periphery of the impeller blades 27 and plate 33, the walls of the chamber 24 below the blades 27 and plate 33 being of a larger diameter for providing a greater clearance. This feature of greater clearance for the seal box is optional. The main throat 28 is of approximately twice the length of the bypass throat. The significance and novel mode of operation introduced by this ratio of the throats is fully explained and disclosed in my copending application, Serial No. 439,308, above referred to. Suffice it to say that with a length of the priming throat of from 30% to 60% of that of the main throat, and both throats narrower in width than the blade channel, the efficiency of the pump for both priming and liquid pumping is greatly improved. The openings 28 and 29 which are termed ports are the most constricted part of the pasageways 28a and 29a. The blades 27 substantially sweep the channel or pumping space in which they operate. That is to say, the impeller chamber is concentric with the impeller, and the impeller has the usual tip clearance for this type of pump.

The impeller blades 27 are shown as straight blades which may be eight in number, or of any other desired number, but it is to be understood that the blades may be curved, or may be otherwise arranged than as straight radial blades. The blades 27 are open at the upper side, and terminate at their inner ends about even with the opening through the bottom of the intake chamber 17, providing a recess for the more ready flow of liquid being pumped into the blades. The blades 27 are formed integral with a disk 33, which disk closes the space between the blades at the bottom. That is, the impeller

is a semi-enclosed impeller. The disk 33 has a depending flange 34 which is threaded internally to receive the threaded flange 35 on the disk 36, which latter disk forms the bottom of the sealing box or sealing channel member. An outwardly extending flange 37 provides a shoulder against which the end of the depending threaded flange 34 abuts, and these two parts, 34 and 37, may be welded together to provide a unitary structure which is leakproof. The bottom wall 36 of the sealing box is in this embodiment formed integral with the impeller shaft 38. This construction provides an integral leakproof seal box or sealing channel member.

A sealing sleeve 39 has a shoulder 41 bearing against the edges of the annular flange 37 formed on the bottom of the wall 4 against which it is clamped by a nut 44 threaded upon the reduced upper end of said sleeve. The sleeve 39 below the upper threaded portion is provided with a shoulder so as to receive a yielding packing ring 48 under the locking washer 45. The locking washer 45 shown in plan in Figure 2 has a keying projection 46 entering a keyway formed in the adjacent part of the sleeve, and it has a pair of arms 47, 47 adapted to embrace the inner part of the suction connection 18. Thereby the main body of the washer 45, operating through the key 46 and keyway on the sleeve 39, cannot turn in respect of said sleeve 39. Because of the projections 47, 47, this assembly is then prevented from turning relative to the boss 31 in which the upper end of the sleeve seats and is clamped by the nut 44. It will be observed that by this construction the packing 48 is renewable in the event that it should be desired to disassemble the pump, or even to repack this particular joint. Furthermore, the packing is out of the current of liquid, which may be corrosive or destructive of the packing.

At its lower end the sleeve 39 carries the integral disk 40, which cooperates with the channel formed in the sealing member or box in the manner disclosed in my copending application, Serial No. 439,308 aforesaid. The top wall 36 of this sealing chamber or box carries on its underside, that is, inside the box, the blades 42, which extend to the outer periphery of the disk 40. The lower wall 36 of the sealing box or channel chamber has blades 43 extending out to a point short of the periphery of the sealing disk 40, there being a gap 49 between the flange 35 and the outer margin of the sealing disk 40 of such character that no substantial pressure is developed by the rotation of the parts relative to each other. The clearance 49 may be $\frac{1}{16}$ of an inch, or more, between the flange 35 and the margin of the disk 40, but the blades 42 and 43 have substantial depth of about $\frac{1}{16}$ inch or more so that pressure is developed in them in accordance with the speed of rotation, the diameter of the blades and the density of the medium acted upon. The longer blades 42 are disposed on the suction side of the plate or disk 40, so that pressure is developed at the full tip of the disk 40 by movement of the impeller shaft and the sealing box. No substantial pressure is developed in the gap 49 between the margin of the disk 40 and the flange 35, but liquid will be retained therein for sealing purposes. In the event of entry of liquid into the blades 43, they will develop pressure in accordance with their diameter, but in no case can they develop the same pressure which is developed in the blades 42. Thus the desirable action of maintaining a

full development of pressure in the blades 42 as against atmospheric pressure will tend to maintain a liquid seal in the gap 99 between the flange 35 and the margin of the disk 40. If, however, the pressure difference is less than that for which the blades 42 are designed to meet, liquid will flow into the lower blades 43 and develop a counter-pressure. The result of this construction is that the liquid seal is capable of developing as against the pressure difference upon the seal, due to suction in the pump, full pressure developed by the blades 42, and yet if this suction is released, liquid will not be discharged up through the clearance between the shaft 38, and the sleeve 39 by the action of the blades 42, since that is balanced by pressure developed by liquid in the blades 43. The result is that the liquid seal is maintained throughout conditions of operation from full atmospheric on both sides of the seal to atmospheric on the lower side and full suction on the upper side of the seal.

It will be observed that the top wall 33 is annular and provides a substantial clearance between the sleeve 39 which is somewhat thickened at the lower end in the form illustrated. It is also to be observed that the lower end of the shaft 38 has an enlargement providing a shoulder 44 normally having ample clearance but engageable with a shoulder formed on the sleeve 39, this being for the purpose that when the sleeve 39 is thrust downwardly for disassembly purposes, the shoulder 44 on the shaft will engage the cooperating shoulder on the sleeve to thrust the shaft 38 downwardly, without putting stress upon the rather fragile disk 40. These interengaging shoulders might be anywhere along the length of the shaft 38 and sleeve 39.

The sleeve 39, the sealing box and impeller and its shaft are formed as a unit for assembly and for replacement. This is the preferred form of the device. I have found that by fusion joining these parts together not only is there complete freedom from leakage, but the predetermined relation between the parts is assured upon replacement of the unit. The shoulder 41 on the sleeve 39 and the shoulder on the upper end of the shaft 38 are adapted to be located against the bottom of the boss 51 and the cap 72 on the lower end of driving shaft 60, respectively. When these parts are so engaged the disk 40 on the lower end of the sleeve 39 will be properly located in the sealing box 34.

The impeller and seal box have a clearance with the side walls and the bottom walls of the chamber member 24. This clearance may be of the order of $\frac{1}{8}$ " to $\frac{1}{4}$ " more or less. Preferably, the inside sidewalls of the member 24 are slightly enlarged below the portion 24a of the casing walls which cooperate with the blades 27 as indicated at 24b on Figure 6. The impeller and the appropriate part of the impeller chamber 24 may be of greater diameter than the seal box by stepping the diameters accordingly. With a disk 40 of substantially $4\frac{1}{4}$ ", and with the construction of the blades 42-43 and non-pressure developing clearance 99 in the seal box shown herein, full difference between maximum suction and atmospheric pressure may be maintained by a shaft speed from 2900 R. P. M. up to any higher value. For a shaft speed of 1750 R. P. M., I have found a 7" disk to function satisfactorily to hold the seal against maximum suction. This data is for operation of the seal with water.

The bottom of the cup-shaped member 24,

which forms the impeller and seal box housing, is provided with a drain opening 50 which may be disposed at the center of the same, and may be either normally open or normally closed as desired, or it may be disposed off at one side, and if it is open, it may be employed as an auxiliary priming port, as hereinafter described. The top wall of each duct 28a which is formed integral with this member 24 is provided with an air venting opening 52 which extends out to the separator chamber 20. This opening 52 serves to function in the operation of the pump of reducing the time required for the pump to start its orderly operation of taking in priming liquid and evacuating air, as will be described more in detail later.

As shown in Figure 3, an auxiliary priming port 53 for entry of liquid may be located at the bottom of the side wall of the impeller chamber member 24. Alternatively, it may be located in the bottom wall near the side wall, i. e., under flange 31. The function and mode of operation of this auxiliary priming port 53, and the function and mode of operation of the air escape port 52, will be explained in connection with the operation of the pump as a whole.

The bearing barrel 8 comprises a tubular member provided with a flange 55 at its lower end, resting in a recess in the annular bridge plate or ring 7 which in turn rests upon the top of the upper end of the side walls 5. A suitable drain opening, not shown, through the side wall 5 above the closure wall 4 provides for the drain of any liquid which enters the space within these walls. Also a hand-hole, not shown, which may be covered by a plate, is provided through the side wall 5 for manipulation of nut 94. The motor support member 9 comprises an upper annular ring 57, and a lower annular ring 58 connected by suitable columns 59, which may be joined by webs, or may be separate as desired. Preferably the front part of the motor support 9 is open to permit access to the coupling not shown, which the motor shaft makes to the shaft section 60 carried in the barrel 8. The motor support 9 and the bearing barrel 8 are clamped to the ring 7, and to each other by the bolts 62. The bearing barrel 8 has a cap or cover 63, with an oil duct 64 through which oil may be conducted to the upper ball bearings 65, and then the oil may run by gravity to the lower radial and thrust ball bearings 66. The inner races of the two sets of ball bearings 65 and 66 are clamped by shoulders and threaded nuts 67 and 68 to the shaft section 60. The outer race of the bearings 65 rides loosely in the upper end of the barrel 8, and the outer race of the bearing 66 is fixedly supported by the bearing clamping ring 69 which clamps the outer race between a shoulder on the lower end of the bearing clamp ring 69 and the lower end of the barrel 8. The shaft section 60 and the bearings are adapted to be withdrawn downwardly from the bearing barrel 8 by release of the bearing clamping ring 69, which is held by bolts 70. Thereupon the shaft section 60, with its bearings 65 and 66, may be withdrawn downwardly in respect of the barrel 8 or vice versa. A protecting ring 72 is secured by a press or shrink fit upon and over the end of the shaft section 60. This protecting ring has a radially extending body with a cylindrical flange 73 for sealing purposes. An annular oil channel member 75 is supported by an integral ring 76 against the bottom of the bearing clamping ring 69 being held by bolts 70. This channel ring 75 has an outlet 77 through which excess oil

and other liquid may be drained. The vertical cylindrical flange 73 has rather close clearance, but is out of contact with the bearing clamp ring 69 and the ring 76 of the channel member 75, so that a film of oil normally seals the adjacent surfaces of the members 69, 73 and 76 when running, and a pool of oil is trapped inside of 73 when standing. When the shaft stops spinning, the oil runs down through the bearing 66 and collects in a pool which floods the lower end of bearing 66 before it spills over the edge of the flange. Thus the shaft when it starts up has its heavy duty bearing 66 flooded with oil. The upper bearing on starting up receives oil from a cup through duct 64. Thus both bearings are 15 promptly lubricated on starting up the pump.

Even with this liquid seal, I discovered that there is danger of breathing of the space within the hollow barrel 8 when the barrel becomes warmed up by the friction of the rotating shaft 20 and subsequently cools. It is undesirable to provide openings in the barrel 8 to permit entry and exit of air to satisfy this expansion and contraction of the air inside of the same, because it tends to draw in impurities which contaminate the bearings. I solved the problem by providing a filler block 78 which reduces the clearance between it and the shaft section 60 to so small a volume that breathing is inconsequential. Thus no appreciable vapors or air are drawn in and no dirt or foreign substances can enter the bearings.

The pump discharge connection 19 has an enlargement 78 which is adapted to house a flow retarding body, such as the ball 79. The ball 79 may move between the integral stop 80 at the rear and the removable stop 82 at the front. This stop 82 is preferably mounted on a stud which extends up through the wall of the enlargement 78, and is held by a nut 83. A shoulder 84 may be disposed on the bottom wall to cooperate with the stop 82 and prevent sticking of the body 79 between the stop 82 and the floor of the chamber. The body 79 is not large enough to completely fill the opening in the connection when it is against the back stop 80, but in that position it acts to retard backward flow of liquid from the discharge pipe (not shown) which is connected to the connection 19. When the ball 79 is in its forward position against the stop 82, there is ample room for full discharge of liquid around the ball 79, and out the connection 19.

The pump body is supported upon a stand 85, being held thereupon by three or more cap screws 86 threaded into bosses 88 through openings in a supporting flange 87. The bottom of the stand may have a suitable flange or feet 89, with bolting openings therethrough to secure the stand 85 to a suitable mounting.

The bottom section 12 of the pump body is provided with a drain plug 90 through which the interior of the pump may be suitably drained. The central opening 50 in the impeller chamber member 24 may be connected with transverse grooves such as illustrated in Figure 9, so that the impeller chamber may likewise drain out through the opening of the drain plug 90. The impeller chamber member 24 is preferably keyed to the bottom section 12 to prevent any rotation of the said member 24 when it is in place, as by means of a projection 92 formed on the member 24, this projection 92 engaging with a boss, not shown, formed in the bottom wall 3 at a suitable place.

The impeller shaft 38 is telescopically socketed

in the lower end of the driving shaft 60, and pulled tightly into place by the axial tie bolt 93, which pulls the shoulder formed on the upper end of the impeller shaft 38 against the ring 72 to make a fluid-tight joint at this point. A key 91 is set in a keyway above the ring 72, and it enters a keyway formed in the upper end of the shaft 38 to key the driving shaft section and the impeller shaft 38 together.

When it is desired to renew the impeller, shaft, and seal unit, the pump is first opened by removing the top part or section 10 from the bottom section 12, or vice versa, and likewise removing the impeller chamber member 24. The tie bolt 93 is unscrewed, the motor being first removed, and the nut 94 is then threaded upwardly, that is backed off, until it engages the bottom of the ring member 72. It then acts as a screw jack to force the sleeve member 39 to engage the shoulder 44 on the lower end of the impeller shaft 38, and to pull the impeller shaft outwardly out of the socket in the shaft section 60, and to push sleeve 39 down in opening 41 of boss 51. The shaft 38, sleeve 39, impeller 27 and sealing box are then removed as a unit, and may be replaced by a new unit with fresh packing at 93, and the pump reassembled and put into operation.

In the operation of the pump, assuming that the pump is provided with a charge of priming liquid, this liquid enters the impeller chamber, flows into the impeller blades, and down through the opening between the sleeve 39 and the top of the sealing box, and fills the sealing box. The clearance between the shaft 38 and sleeve 39 may be any suitable ample running clearance which keeps these parts out of contact. In other words, the shaft, the sealing box and the impeller run freely without contact or close clearance with any stationary part. Since entry of liquid at the top can force air out through the clearance between the sleeve 39 and the shaft 38, the liquid seal is immediately filled and established for operation. Assuming that the suction connection 18 is connected to a suitable pipe and the suction pipe is sealed with liquid which it is desired to pump, the shaft 60 will be driven by the motor which is suitably connected to it. Thereupon liquid standing in the impeller and in the intake chamber 17 will immediately be thrown out through the ports 26 and 28 and discharged into the separator. Gas follows, this gas usually being air, and since air is of so light density, being only about $\frac{1}{800}$ of the density of liquid, the impeller is not able to blow air of so slight density out against the head of liquid in the separator. However, with a slight amount of liquid which tends to come in through the ports, a medium somewhat denser than air, but far from as dense as liquid tends to be initially formed, and even this medium may not be of sufficient density to start delivery through the ports 28 and discharge ducts 28a, since there is a slight head of liquid of the priming charge above these parts. Particularly the driving of gas, that is air, out into the priming throats 29, tends to trap air, in view of the fact that the outer ends of the ducts 29a dip down below the flange segments 30. Liquid will slowly be worked in through the rapidly rotating blades and will eventually overcome the so-called "priming stall," which is due to the failure of sufficient liquid to reenter to establish an orderly circulation. In the present pump structure, I have provided two independent means for accomplishing the overcoming of this "prim-

ing stall," one being the provision of an auxiliary priming port which may be through the port 50 or 53, which will allow liquid to seep up through the clearance and into the space between the blades 27, thereby forming a denser mixture which will begin to form a flow tending to discharge out through the throats 28 in sufficient force and volume to establish a discharge. Thereby, by supplying additional liquid in through the clearance between the rotating sealing box and the chamber member 24, the "priming stall" may be overcome. Upon the pump becoming primed and filling its intake with liquid, delivery pressure is established.

The pressure developed by the blades 27 and prevailing at their tips tends to pass through the clearance and down along the sealing box, and out the opening 50. However, this is counteracted by the bottom rotating wall of the sealing box to an extent which tends to retard or may completely check the inward flow of liquid at the port 50. In fact, the bottom surface of the sealing box, that is, the disk 36, may be bladed, as at 100, in order to set up a counter-pressure to that of the blades 27. Inward flow from the separator through opening 50 or 53 is counteracted by internal pressure.

Instead of having the auxiliary priming port at the center of the chamber 24, it may be located at the periphery as indicated at 53 in Figure 3, or it may be formed through the bottom wall of the chamber member 24, at a less radius than the inner cylindrical walls of the said chamber member 24.

It is not necessary that the pressure be completely reversed, that is, raised to a degree to cause liquid to be discharged out of the opening 50 or 53. It is sufficient merely if the flow be reduced to a value which is inconsequential upon the efficiency of the pump. However, this method of supplying additional liquid which will make up a dense enough medium to start the orderly discharge of mixture and reentry of liquid at the priming ports will reduce the time of the so-called "priming stall," and accelerate the establishment of orderly evacuation of air from the suction pipe. As soon as this orderly circulation is established, the impeller blades discharge a mixture of air and liquid out through the main throats 28 and receive reentry of priming liquid at the priming throats 29.

As heretofore stated, the priming operation is usually divided into three stages, namely, the first stage which involves establishing an orderly circulation and filling of the discharge throat with a stream of mixture which terminates the first stage or "priming stall" stage. The end of the second stage may be recognized by excessive inflow of liquid due to suction on the intake side, resulting in the forcing by atmospheric pressure of liquid through the return throats 28 in more than adequate volume. From then on the third stage tends to remove air until a point is reached where no further air can be evacuated by the pump at the speed and under the conditions under which it operates.

An alternative method of shortening the period of the "priming stall" is to provide a ready escape for air out of the main throat, as by means of the openings 52 in the top wall of the ducts 28a at the throats 28. A $\frac{1}{4}$ inch opening 52 in one or both of the two ducts 28a tends to allow the air to gravitate out without requiring the establishment of a regular dis-

charge stream of mixture greatly shortens the initial "priming stall" period. In experiments which I have conducted, the "priming stall" was cut from 120 seconds to 60 seconds by the expedient of air discharge openings 52 in the main ducts 28a. No substantial interference with the efficiency of the pump was caused by the presence of the air evacuating openings 52, and such openings 52 may be employed without the introduction of liquid through the auxiliary priming ports 50 or 53 above referred to.

Upon shutting down the motor, the impeller and its sealing box tend to slow down to a point where the pump will no longer deliver liquid through the discharge, or in other words, will no longer maintain the delivery pressure and the air seal. As soon as the delivery pressure drops below the head against which the pump is operating, the liquid will tend to flow back in the discharge and to flow back down the suction pipe, and, as per my experience without the flow retarding means shown in Figure 1, if the discharge and suction connections are wide open, the dropping of the column in the suction pipe is very rapid, and will rapidly pull liquid down through the discharge pipe, followed by a rush of air, which practically cleans the liquid out of the pump, tending to rob it of its priming charge.

I have heretofore employed a flow retarder in the suction connection, as shown in my copending application above referred to. But I have discovered that there are certain conditions under which the flow retarder in the suction connection produces unsatisfactory results in that checking of the downflow of the suction column does not prevent full pressure of the discharge column from being exerted upon the sealing box and sleeves, with the result that liquid may be squirted out of the sealing sleeve 39. Where the liquid being pumped is either corrosive, or inflammable, this is objectionable. It is undesirable at all events. I conceived the employment of the flow retarder 79 in the discharge connection, and with the structure shown in Figure 1, when the impeller slows down to the point where the discharge pressure cannot be maintained, liquid drops in the suction connection and pulls air down through the sleeve 39, through the sealing box, and out through the suction connection to follow the retreating column of liquid. Since the return of liquid from the discharge pipe is retarded to a relatively slow return, the suction connection may be completely emptied of liquid and filled with air, while the liquid from the discharge pipe then slowly returns to the separator 20, from whence it flows through the impeller chamber and into the intake connection 17. Any excess drains out through the suction connection 18. It is to be observed that the bottom wall of the suction connection 18 is substantially below the top of the sleeve 39, so that the return of liquid may fill the pump and drain back into the suction connection without flooding the seal, i. e. running out of the top of the sleeve 39. A drain may be provided for the space above the closure wall 4 for the draining of any liquid back to the source if so desired.

Even if no substantial body of liquid is retained in the discharge pipe as would be the case when the pipe leads downwardly from the neck 19 the flow retarder 79 appreciably restricts flow of air down through the separator and hence tends to cause air to flow through

the seal to break the vacuum in the intake. While the pump above described in connection with Figures 1 to 8, inclusive, is made of a suitable metal, designed to resist the attack of the particular liquid being pumped, the invention may be embodied in a porcelain pump, that is, a pump where the main body portion and so much of the impeller chamber and other parts as possible are made of porcelain, or other non-metallic moldable material suitably resistant to the liquids which it may be required to pump.

In Figure 9 I have illustrated a porcelain pump of a structure such that the main working parts which are necessarily made out of metal may be interchangeably employed in either the metal body pump or the porcelain body pump.

In the body of the pump shown in Figure 9, the top section 10 and the bottom section 12 are made of porcelain, the meeting edges of which are ground off to provide sealing surfaces with a gasket 102 interposed. Matching bolt holes 103 receive the clamping bolts 104, 105 which extend vertically through the openings 103 to hold the pump upon the base and to clamp the two parts 10 and 12 together. The shorter bolts 105 contain, intermediate their ends, transverse pins 106 lying within an annular groove formed in a metallic ring 108, which ring is set in an annular recess in the lower margin of the top section 10 of the pump body. This metallic ring 108 serves as a clamping or binding means for the lower edge of the side walls of the upper section 10, and prevents the application of any sharply concentrated stress which the pins 106 would otherwise apply when the upper part of the bolt is put under tension by screwing down the nut 107.

Three or more bolts, such as 105, spaced around the circumference of the body, permit through the pin 106, ring 108 and nut 107 in each case, of clamping the bearing support ring 7 to the top of the cylindrical walls of the upper section 10. On the same bolts 105, nuts 109 at the lower end clamp the bottom section 12 against the top section 10. The longer bolts 104 extend through raised bosses 110, so as to distinguish them from the shorter bolts 105 and they carry nuts 112 at their upper ends. The bolts 104 serve to clamp the pump as a whole including its bearing barrel and motor support upon the supporting base or bracket 85. The bolt 104 in each case carries a nut 113 at its lower end below the flange 87 of the bracket or base 85, and it extends through a collar 114 and a soft lead washer 115, and then extends on up through the matching bolt holes 103 in the bottom section and the top section, and through the flange 7 and its distinguishing boss 110. At the upper end the nut 112 puts tension upon the bolt 104 to hold the pump upon the base. The pump may be removed from the base 85 by releasing the nuts 112 which are distinguishable by the bosses 110.

The pump as a unit may then be lifted completely from the base. Thereupon, to remove the lower section 12, the nuts 109 of the shorter bolts 105 are unscrewed, and the cup-shaped bottom section 12 may be slid downwardly on the guiding lower ends of the bolts 105. The porcelain impeller and sealing box member 24 may be dropped down with the bottom section 12. If it is desired to remove the ring 7 with its motor support and bearing barrel as a unit, this may be done by releasing the nuts 107 on the top end of the shorter bolts 105.

The arrangement of unitary impeller shaft, sealing box and sealing sleeve shown in Figure 1 may be interchangeably employed in the construction of the pump shown in Figure 9. Likewise, the separable arrangement of these working parts as shown in Figure 9 may interchangeably be used in the body of the pump shown in Figure 1.

The assembly of the driving shaft section 80 and the impeller shaft 36, sleeve 39, impeller and seal box, is the same as shown in Figure 1. In fact, these working parts are identical for both the metal pump of Figure 1 and the porcelain or non-metallic pump of Figure 9. Except for the difference in assembly and disassembly of the body parts of the two pumps, the servicing of the two pumps is the same.

Referring to Figures 4, 5 and 8, the priming passageway which opens below the plate 30 is extended substantially to the outer edge of the plate 30 to insure that the outer end of the passageway is sealed with liquid during priming. Figure 7 indicates the sections on stations 1 to 11 along the axis of the main discharge passageway 28a and its throat 28, as indicated on Figure 4. Similarly Figure 8 shows similar sections taken on similar stations of the priming passageway 28a and its throat 28.

The flow retarder in the discharge connection previously described in connection with Figure 1 is also employed in the embodiment of Figure 9.

A suitable drain plug 90 is provided in a metallic insert 125 disposed in the bottom wall of the pump, as shown in Figure 9.

The draining opening 50 shown in Figure 9 is connected to lateral branches formed by a transverse groove, through which communication between the discharge chamber or separator 29, and the interior of the impeller and sealing box chamber 24 is provided.

It is to be understood that like reference numerals in Figures 1 to 8 and in Figure 9 indicate like parts, and that the operation of the pump described in connection with the embodiment of Figures 1 to 8 applies also to the embodiment of Figure 9.

The pump herein disclosed provides a structure which solves the problems above mentioned, the essential novelty of which is intended to be covered in the appended claims.

I do not intend to be limited to the precise details shown and described, except as they are made essential by the appended claims.

I claim:

1. In a vertical self-priming pump, a cylindrical hollow body comprising substantially cylindrical side walls, an upper closure wall below the top of said side walls, a bottom wall, walls depending from said upper wall defining an intake chamber, a cup-shaped impeller chamber member resting on said bottom wall and being telescopically joined to said walls of the intake member, an impeller in said impeller chamber, a shaft therefore extending through said upper closure wall, means for maintaining a seal about said shaft, a mounting ring resting upon the upper end of said sidewalls, a driving shaft barrel resting on said mounting ring, a driving shaft section having antifriction bearings in said barrel and being joined to said impeller shaft, a suction connection extending through the upper part of said sidewalls above said closure wall and opening into said intake chamber, and a discharge connection extending through the upper part of said sidewalls 75 above said closure wall and opening into the

space between said depending walls and said cylindrical sidewalls.

2. The pump of claim 1 wherein the shaft is sealed to the upper closure wall by a sleeve and liquid seal box, said box being disposed in the bottom of said impeller chamber member and below the impeller.

3. In a pump of the class described, a cylindrical hollow body comprising substantially cylindrical side walls, a top closure wall and a bottom wall, the sidewalls extending above the closure wall, a bearing barrel supported on said extended sidewalls and spaced from the top closure wall, internal walls defining an intake chamber within the upper end of the hollow body there being a separator chamber outside said internal walls and inside the hollow body, an impeller chamber member cooperating with the lower end of said internal walls to form an impeller and sealing box chamber, a unitary sealing box and impeller having a central vertical shaft section, a sealing sleeve having a sealing disc in said box and having its upper end projecting through and sealed to the top closure wall, and a driving shaft section in said bearing barrel joined to said impeller shaft section.

4. The pump of claim 3 wherein said shaft section provides a shoulder above the sleeve, the upper end of the sleeve having a nut threaded thereupon and engageable against the shoulder to force the sleeve downwardly when the nut is backed off the sleeve.

5. In a pump of the class described, a hollow pump body having a top wall and sidewalls extending above the same to provide a bearing support for a shaft, a shaft supporting barrel resting on said walls, a sealing sleeve extending through and shouldered against the bottom of said top wall, a driving shaft section supported radially and axially in said barrel, an impeller shaft section extending up through said sleeve and being coupled to the lower end of said driving shaft section, a nut threaded upon the upper end of the sleeve to clamp the sleeve with its shoulder against the bottom of the top wall, said nut being engageable against a shoulder on the driving shaft section to force the sleeve downwardly when the nut is backed off.

6. The combination of claim 5 wherein a shoulder on the sealing sleeve is engageable with a shoulder on the lower end of the impeller shaft section to transmit thrust on the sleeve to the impeller shaft section whereby the impeller shaft section and sleeve may be forced down together by backing off said nut.

7. In a pump having a hollow body including sidewalls and an upper closure wall, a sealing sleeve extending through said closure wall and shouldered against the bottom thereof, an impeller shaft extending up through said sleeve, a bearing barrel secured to the top of the pump and spaced from the top closure wall, a driving shaft section mounted in antifriction bearings in said barrel and having its lower end socketed to receive the top of the impeller shaft, a clamping and releasing nut threaded upon the upper end of the sleeve, said nut on backing off being engageable with said driving shaft section to force the sleeve down.

8. In a vertical self-priming centrifugal pump having a hollow body with a top closure wall, a liquid shaft sealing sleeve extending up through the said wall, an impeller shaft extending down through said sleeve and carrying an impeller, there being an intake chamber and a separator

chamber in said hollow body and an impeller chamber between said chambers, a kinetic sealing channel and a disc between said sleeve and shaft having an annular gap between them opening into said impeller chamber, a suction connection for said intake chamber adapted to be connected to a suction pipe, a discharge connection for said separator chamber adapted to be connected to a delivery pipe, and a flow retarder in said discharge connection for retarding but not stopping the return flow of liquid from the discharge pipe, said gap permitting air to be drawn therethrough into the suction pipe to allow liquid therein to drop freely while said flow retarder restricts the flow of fluid from the discharge pipe into the separator chamber.

9. The combination of claim 8 wherein the flow retarder comprises an enlargement in the discharge connection, a movable retarder body in said enlargement and a pair of stops for limiting the extreme positions of said body, one stop being adapted to stop the body in a position in said discharge connection where the enlargement provides free passageway around the body for discharge of liquid, and the other stop being adapted to stop the body in a part of the enlarged body where restricted passageway around the body retards the return flow of liquid.

10. A pump of the class described comprising a closed hollow body of vitreous material, said body having substantially cylindrical sidewalls divided horizontally, vertical bolt holes through the sidewalls for clamping bolts, the lower section comprising a top closure wall below the top of the sidewalls, internal depending walls joined to the top closure wall for defining an intake chamber internally thereof, a vitreous impeller housing and duct member resting upon the bottom wall and telescoping with the lower end of said depending walls to define an impeller and sealing box chamber, an impeller and sealing box in said latter chamber, a sealing sleeve extending from said sealing box up through the top wall and clamped thereto, an impeller shaft carrying at its lower end the sealing box and impeller extending up through said sleeve, horizontally extending suction and discharge connections extending from said sidewalls above said closure wall, a metallic bearing barrel having a mounting flange resting upon said sidewalls, a driving shaft section having bearings in said barrel and coupled to said impeller shaft, and clamping bolts extending vertically through said flange and the longitudinal bolt holes for clamping said parts together.

11. In a vertical pump having a hollow body with a top closure wall, a liquid seal sleeve opening upward through said top wall, an impeller shaft extending through said sleeve, a hollow bearing barrel disposed above said top closure wall, the lower end of the barrel being disposed adjacent the top of the sleeve, a driving shaft section having spaced antifriction bearings carried on the shaft and mounted in said barrel, said shaft section being joined to said impeller shaft, and a cylindrical filler block in said barrel between said spaced bearings closely embracing said shaft for reducing the space inside said barrel to prevent changes in temperature of said barrel bearing from breathing vapors of corrosive liquids handled by said pump into the bearings.

12. For use in a pump of the class described as an article of manufacture, a unitary impeller chamber and duct member comprising a cup-

shaped body having pairs of ports through the sidewalls thereof for the passage of liquid, segmental flanges, one for each pair of ports, and duct containing nozzles for said ports, one nozzle of each pair opening above the corresponding flange segment and the other nozzle of each pair opening below the corresponding flange segment.

13. The article of claim 12 having a central boss on the bottom for supporting the same, and a keying shoulder disposed laterally of the boss for preventing angular movement of the member in use.

14. In a vertical pump of the class described, a horizontally disposed impeller casing, an impeller rotatable therein in a horizontal plane, said casing having internally thereof a peripheral channel which is substantially swept by the impeller, said casing having a main discharge duct opening through a port into said channel, a priming duct opening through a port adjacent said first port into said channel, the pump having a casing with walls defining a separator chamber in which said impeller casing is disposed, said ducts extending in a generally horizontal direction and opening at their outer ends into said separator chamber, there being an opening for escape of air during the initial stages of priming extending through the top wall of said first duct adjacent the junction of said duct and said channel.

15. In a vertical pump of the class described, a horizontally disposed impeller casing, an impeller rotatable therein in a horizontal plane, said casing having internally thereof a peripheral channel which is substantially swept by the impeller, said casing having a main discharge duct opening through a port into said channel, a priming duct opening through a port adjacent said first port into said channel, the pump having a casing with walls defining a separator chamber in which said impeller casing is disposed, said ducts extending in a generally horizontal direction and opening at their outer ends into said separator chamber, there being an auxiliary priming opening in the lower part of the impeller casing for reentry of priming liquid into the impeller during the initial stage of priming.

16. In a pump of the class described, a cylindrical body of vitreous material formed in two sections with meeting annular faces, shaft bearing support means on the upper section, the lower edge of the top section having an annular recess, a ring disposed in said recess, there being vertical bolt holes through the bearing support and the cylindrical walls of the two sections and the interposed ring, bolts lying in said holes, said bolts having shoulders for engaging the ring and nuts at the upper ends for holding the bearing support upon the upper section, and nuts on the lower ends of the bolts for removably supporting the lower body section.

17. In combination with the pump of claim 16 of a base for supporting the pump and bolts independent of the first named bolts extending through the bearing support means, the cylindrical walls of the pump body and attached to said base.

18. In a pump of the class described, a body comprising two main sections of substantially cylindrical form, namely, a cup-shaped bottom section and an inverted cup-shaped top section, said sections defining a separator chamber, the top section having a centrally perforated top wall and a depending annular wall joined to the top wall near the junction of the top wall and side

wall to define an intake chamber, said top section having a substantially cylindrical flange wall extending above its top wall, an annular plate disposed on said flange wall, a bearing barrel for a drive shaft supported on said annular plate, a cup-shaped impeller and seal chamber member telescopically joining the depending annular wall and resting on the bottom of the bottom section, said impeller and seal chamber member having openings defining ports and passageways for discharge and reentry of liquid between the inside and outside of said latter member, a sealing sleeve secured at its upper end in said central perforation of the top wall of the top section and bearing a sealing disc at its lower end, a rotor comprising a channel member open at the top and closed at the bottom and bearing impeller blades cooperating with said ports and passageways, a shaft secured to said channel and impeller member and extending through said sleeve and having bearings in said bearing barrel, and discharge and intake connections extending through said flange wall of the top section and communicating with said separator and with intake chamber respectively.

19. A renewable unit comprising a sleeve having its upper end threaded, and having a disk on its lower end, an impeller shaft carrying a circular sealing box providing an internal annular channel cooperating with said disk to provide a kinetic liquid seal, the bottom and sidewalls of the box being closed, the top wall having an opening closely surrounding the sleeve, impeller blades mounted on the top wall of the box in a plane at right angles to the shaft, said sleeve having an upwardly facing annular locating shoulder, and said shaft having a locating shoulder, said shoulders being adapted to bear against cooperating shoulders on a stationary part and a rotating part, said latter shoulders being so spaced as to ensure a predetermined location of the disk in said sealing box.

20. The unit of claim 19 wherein the sleeve and the shaft have facing annular shoulders adapted to be engaged endwise when the sleeve is moved downwardly along the shaft whereby the movement of the sleeve downwardly will carry the shaft with it.

21. In a vertical self-priming pump, a hollow pump body comprising an upper transverse wall having a central opening, walls defining an intake trap below said top wall, said trap being open at its bottom, a sealing sleeve having its upper end removably secured and seated in said central opening, a sealing disc mounted on the lower end of said sleeve, an impeller shaft extending down through the sleeve and bearing a channel ring member having an internal channel embracing the margin of the disc, impeller blades carried on said channel ring member, an impeller chamber member having a cylindrical recess and peripheral throats cooperating with said blades, said latter member cooperating with the lower margins of said intake trap walls about said bottom opening to define an impeller and seal chamber, and said pump body comprising walls defining a separator chamber outside of and surrounding said impeller chamber and communicating with said throats.

22. The pump of claim 21 wherein the impeller chamber member is a substantially cup shaped member piloted upon said margins of the intake trap wall, and the lower part of the body wall forming the separator chamber is a cup shaped

member upon the inside of which is seated said impeller chamber member.

23. The combination of claim 21 wherein the pump body has side walls extending above the upper transverse wall, a bearing barrel having anti-friction bearings and a drive shaft section therein supported upon said walls, said drive shaft section and the upper end of the impeller shaft having a telescopic driving connection.

24. A unitary impeller and seal structure comprising a sleeve shouldered externally at a point adjacent its upper end and threaded at its upper end to receive a clamping nut, an annular disc integral with the lower end of the sleeve, an impeller shaft extending through the sleeve and bearing a boxlike channel member embracing the margin of the disc, said channel member being open at the top where it embraces the sleeve and bearing impeller blades to constitute a pumping impeller, said sleeve and impeller shaft having interengaging shoulders for transmitting thrust exerted downwardly upon the sleeve directly to the lower end of the impeller shaft.

25. In a centrifugal pump, an impeller and seal structure comprising a sleeve shouldered externally at a point adjacent its upper end and threaded at its upper end to receive a clamping nut, a clamping nut engageable on said threaded upper end, an annular disk integral with the lower end of the sleeve, an impeller shaft extending through the sleeve and bearing a boxlike channel member embracing the margin of the disk, said channel member being open at the top where it embraces the sleeve and bearing at its top impeller blades to constitute a pumping impeller, the sleeve and impeller shaft having interengaging shoulders for transmitting thrust exerted downwardly upon the sleeve directly to the lower end of the impeller shaft, and a driving shaft section telescopically joined to said impeller shaft, said shaft section presenting a shoulder engageable by said nut when the same is backed off to permit the nut to exert a downward thrust upon the sleeve.

HARRY E. LA BOUR.
